CLAIM

We claim the ornamental design for the bicycle pump, as
shown and described.

DESCRIPTION

FIG. 1 is a front isometric view of the bicycle pump, showing
our new design;

FIG. 2 is a front-elevational view of the bicycle pump;

FIG. 3 is a left side-elevational view of the bicycle pump;

FIG. 4 is a right side-elevational view of the bicycle pump;

FIG. 5 is a rear-elevational view of the bicycle pump;

FIG. 6 is a top view of the of the bicycle pump; and,

FIG. 7 is a bottom view of the bicycle pump.

The broken line showing of elements is included for the
purpose of illustrating non-claimed environmental matter and
form no part of the claimed design.
